CLAIM

The ornamental design of an electrical connector, as shown and described.

DESCRIPTION

FIG. 1 is a top, front, and left side perspective view of an electrical connector, showing our new design;

FIG. 2 is a top plan view thereof;

FIG. 3 is a right side elevation view thereof, the left side elevation view being a mirror image thereto;

FIG. 4 is a bottom plan view thereof; and,

FIG. 5 is a front elevation view thereof, the rear elevation view being a mirror image thereto.

The break shown in FIGS. 1, 2, 3 and 4 indicates a cable of indeterminate length.
